COLLECTION BOX OR THE LIKE

Robert Krumholz, 8420 Engleman, Center Line, Mich.

Filed May 18, 1961, Ser. No. 65,222

Term of patent 14 years

(Cl. D58—12)

FIG. 1 is a perspective view of a collection box or the like showing my new design;

FIG. 2 is an end view thereof as it appears with the lid in closed position;

FIG. 3 is a front view thereof; and

FIG. 4 is a top view.

The characteristic features of the design reside in the combination of the inwardly sloped front and side walls wherein the upper edges of the side walls are shaped to engage the lateral lid pintles and then slope downwardly toward the front, turning down abruptly short of the front wall so that the lid in closed position rests between the side walls and projects slightly beyond the front wall, all as shown.

I claim:

The ornamental design for a collection box or the like, substantially as shown and described.
